UNITED STATES PATENT OFFICE

98,549

DESIGN FOR A MIRROR FLORAL DISPLAY DEVICE

Ruth C. Sharp, Islip, N. Y.

Application October 25, 1935, Serial No. 59,210

Term of patent 3½ years

To all whom it may concern:

Be it known that I, Ruth C. Sharp, a citizen of the United States, residing at Islip, Long Island, in the county of Suffolk and State of New York, have invented a new, original, and ornamental Design for a Mirror Floral Display Device, of which the following is a specification, reference being had to the accompanying drawing, forming part thereof.

I claim:

The ornamental design for a mirror floral display device, as shown.

RUTH C. SHARP.
